U.S. Cl. D45—4

FIG. 1

The characteristic feature of my design resides in a watch band of tapered configuration decreasing in width from watch attaching end to clasp and having a row therein of circular perforations of decreasing diameter, the largest perforations at the widest ends and the smallest near the clasp, all as shown.

I claim:

The ornamental design for a watch band, as shown and described.
